CHARLES W. WACHTEL, OF JAMAICA, NEW YORK.

ELECTRIC SWITCH.

No. 900,005.

Specification of Letters Patent. Patented Sept. 29, 1908.

Application filed November 23, 1907. Serial No. 403,439.

To all whom it may concern:

Be it known that I, CHARLES W. WACHTEL, a citizen of the United States, residing at Jamaica, county of Queens, State of New York, have invented certain new and useful Improvements in Electric Switches, of which the following is a specification, reference being had thereto to the accompanying drawing, in which—

16 Figure 1 is a face view of the switch; Fig. 2 a vertical sectional view on the line II—II of Fig. 1; and Fig. 3 a similar view on the line III—III of Fig. 1, showing the switch closed.

The main object of this invention is to provide a switch for use in electric circuits, of exceedingly simple construction, which will be durable and easily secured in place.

A further object of the invention is to provide a switch which may be very cheaply manufactured and which is particularly well adapted for use in circuits having weak currents, such as toys, ordinary household tools and signals, etc.

Referring to the various parts by numbers, 1 designates the base of the switch which is preferably of wood. It will, of course, be understood, however, that the base block may be of any suitable non-conducting material. The switch bar 2 is a 25 piece of non-conducting material, preferably of hard fiber. This bar is shown in the drawing as cylindrical from end to end, but, of course, it may be of any suitable shape in cross-section. Secured to this bar is a metal 30 strip 3, said strip being formed preferably of a piece of wire having its ends 4 turned at right angles to the body of the strip and securely fastened in the switch bar. This contact strip is parallel with the longitudinal 35 center line of the switch bar and it is placed on said bar a suitable distance from the ends thereof.

The switch bar is mounted to oscillate in two bearings or supports 5 which are separated from each other a suitable distance and engage the switch bar outside of or beyond the ends of the contact strip. Each bearing is formed of a piece of sheet metal, preferably brass, which is bent upon itself to form a loop 50 6 which constitutes a bearing for the switch bar. One end of this strip forms a base piece 7 which is adapted to lie against the face of the supporting block 1; the other end forming a clamp member 7^a and lying on the 55 outer side of the base piece. The extreme

free end of the base piece is bent outward or at right angles to the main body thereof to form the flange 8 against which the circuit wire is placed. The extreme end of the clamp member is bent outwardly slightly as 60 at 8^a to permit the circuit wire to be placed thereunder, the outward bent portions of the base piece and the clamp member constituting a clamp for the circuit wire.

To secure the bearings and clamp to the 65 supporting block 1 I use small nails or tacks 9 which are driven through perforations in the base piece and the clamp member and into the block. To secure the block in position and at the same time clamp the circuit wires 70 in place I employ a long screw 10 which is passed through registering perforations in the clamp member and the base piece of the bearing and through the block 1 into the support to which said block is to be connected. 75 The screws 10, therefore, serve not only as circuit-wire securing means, but also as a means for securing the switch block in place. By this means I avoid the use of separate 80 wire fastening means.

Each bearing strip is formed with a contact lip 12 which extends part way around the switch bar on the inner side of the bearing loop 6, as shown clearly in Fig. 1. These contact lips are in such position that the ends 85 of the contact strip may be forced under them, said lips being sufficiently resilient to yield and permit said strip to force them outward. To limit the rotary oscillating movement of the switch bar one of the bearing loops is slotted circumferentially as at 13 in Figs. 1 and 2. Secured to the switch bar and passing through said slot is a pin 14, the length of the slot limiting the extent of oscillating movement of the switch bar. The pin 90 14 also holds the switch bar in the bearings against undue longitudinal movement. To enable the switch bar to be readily turned in its bearings I provide an operating handle 15 secured to one end thereof and projecting 100 radially therefrom.

From the foregoing it will be evident that I have provided an extremely simple electric switch; one which may be readily and cheaply manufactured and which may be secured in 105 place by means of devices which clamp the circuit wires to the switch terminals. The switch bar bearings form the terminals and also the means for clamping the wires in place.

Having thus described my invention what I claim as new and desire to secure by Letters Patent, is:—

1. An electric switch comprising a non-conducting support, two bearings thereon, a rotary oscillating switch bar mounted in said bearings, a contact strip carried by said switch bar, a contact lip carried by each of said bearings and adapted to be engaged by the contact strip on the switch bar, wire clamping means formed integral with the bearings, and means for closing the wire clamping means, said means also serving to secure the switch bar in place.
2. An electric switch comprising a rotary oscillating switch bar of non-conducting material, a contact strip carried thereby and extending longitudinally thereof, a pair of bearings for said bar, each of said bearings being formed of a strip of metal bent upon itself to form bearing loops to receive the switch bar, the two ends of said strip being brought together to form a wire clamp, and a contact lip formed integral with said strip and partly embracing the switch bar and adapted to be engaged by the contact strip of said bar.
3. An electric switch comprising a rotary oscillating contact bar of non-conducting material, a contact strip secured thereto and extending longitudinally thereof, means for supporting said switch bar, said means consisting of two supporting devices each of which consists of a strip of sheet metal bent upon itself to form a bearing loop, one end of said strip constituting a base piece and forming one member of a wire clamp, the other end of said strip lying flat against the base piece and having its extreme end bent to form the other member of the wire clamp, and a contact lip formed integral with one of said ends and partially embracing the switch bar in such position as to be adapted to be engaged by the contact piece on said bar.
4. An electric switch comprising a rotary oscillating contact bar of non-conducting material, a contact strip secured thereto and extending longitudinally thereof, means for supporting said switch bar, said means consisting of two supporting devices each of which consists of a strip of sheet metal bent upon itself to form a bearing loop, one end of said strip constituting a base piece and forming one member of a wire clamp, the other end of said strip lying flat against the base piece and having its extreme end bent to

form the other member of the wire clamp, a contact lip formed integral with one of said ends and partially embracing the switch bar in such position as to be adapted to be engaged by the contact piece on said bar, and means for limiting the oscillation of the switch bar.

5. An electric switch comprising a rotary oscillating contact bar of non-conducting material, a contact strip secured thereto and extending longitudinally thereof, means for supporting said switch bar, said means consisting of two supporting devices each of which consists of a strip of sheet metal bent upon itself to form a bearing loop, one end of said strip constituting a base piece and forming one member of a wire clamp, the other end of said strip lying flat against the base piece and having its extreme end bent to form the other member of the wire clamp, a contact lip formed integral with one of said ends and partially embracing the switch bar in such position as to be adapted to be engaged by the contact piece on said bar, a supporting block, and means for securing the bearings and wire clamp on said block.

6. An electric switch comprising a rotary oscillating contact bar of non-conducting material, a contact strip secured thereto and extending longitudinally thereof, means for supporting said switch bar, said means consisting of two supporting devices each of which consists of a strip of sheet metal bent upon itself to form a bearing loop, one end of said strip constituting a base piece and forming one member of a wire clamp, the other end of said strip lying flat against the base piece and having its extreme end bent to form the other member of the wire clamp, a contact lip formed integral with one of said ends and partially embracing the switch bar in such position as to be adapted to be engaged by the contact piece on said bar, a supporting block, and means for securing the bearings and wire clamps to the supporting block, said means also serving to clamp the wires in place and to secure the supporting block to its support.

In testimony whereof I hereunto affix my signature in the presence of two witnesses this 21st day of November 1907.

CHARLES W. WACHTEL.
